UNITED STATES PATENT OFFICE.

JOHN R. BOARDMAN, OF OKLAHOMA, OKLAHOMA, ASSIGNOR TO WYLIE MANUFACTURING COMPANY, OF OKLAHOMA, OKLAHOMA.

CONCRETE-MIXER.

1,043,391.

Specification of Letters Patent.

Patented Nov. 5, 1912.

Application filed April 23, 1912. Serial No. 692,679.

To all whom it may concern:

Be it known that I, JOHN R. BOARDMAN, citizen of the United States, residing at Oklahoma, in the county of Oklahoma and 5 State of Oklahoma, have invented certain new and useful Improvements in Concrete-Mixers, of which the following is a specification.

This invention relates to concrete mixers 10 and has for its object the provision of a simple and efficient apparatus which may be easily moved from point to point, and by which cement, broken stone, and other elements may be thoroughly and rapidly 15 mixed with very little labor.

Another object of the invention is to provide a concrete mixer in which the mixing drum will be so constructed that the materials to be mixed will be thoroughly agitated and commingled without the use of any complicated structures and discharged from the drum without the necessity of any complicated closures or discharging spouts.

The invention seeks further to provide a 20 drum having internal elements by which, as the drum is rotated, the material to be mixed will be thrown back and forth so as to be thoroughly commingled, the mixture being discharged from the drum upon reverse rotation being imparted thereto.

All these stated objects, and such other objects as will incidentally appear from the following description, are attained in an apparatus of the type illustrated in the accompanying drawings, and the invention consists in certain novel features of construction, combination, and arrangement of parts as will be hereinafter fully set forth.

In the drawings:—Figure 1 is a perspective view of the complete apparatus; Fig. 2 is a transverse section of the mixing drum on a larger scale; Fig. 3 is a longitudinal section of the drum taken on the line 3—3 of Fig. 2; Fig. 4 is a similar view taken on the line 4—4 of Fig. 2; Fig. 5 is a detail perspective view of one of the shelves employed within the drum.

In carrying out my present invention, I employ a truck comprising a pair of wheels 50 1 mounted upon a suitable axle supported in hangers 2 secured to the ends of side bars 3 to which, for the greater portion of their length, is secured a platform 4. At the ends of the side bars or sills 3, distant from the wheels 1, I provide legs or other form

of supports 5 by which the platform may be retained in a horizontal position while the drum is being operated to mix the concrete. A handle 6 is also provided at the adjacent ends of the side bars or sills 3 so that the truck may be easily moved from point to point, as may be necessary.

At that end of the truck which is supported by the carrying wheels 1, I erect standards 7 having a beam 8 secured upon and carried by their upper ends, and upon the said beam, at the end immediately adjacent the platform, I mount a transverse driving shaft 9 equipped with crank handles 10 at its ends and carrying a sprocket pinion 11 adjacent one end. A sprocket chain 12 passes over the said pinion and over a sprocket wheel 13 which is fixed upon a hollow shaft 14 journaled upon the beam 8 at a point remote from the platform, the said hollow shaft carrying the mixing drum 15. The mixing drum is constructed of sheet steel and consists of ends or heads 16 which are rigidly secured to the hollow shaft 14 in any convenient manner, preferably by means of brackets or hubs 17 bolted to the heads 16 and keyed or otherwise fixed to the shaft, and a side 18 which is of a cylindrical formation having a longitudinal opening, indicated at 19, extending between the heads. The cylindrical body 18 is provided with flanges at its ends through which and the heads 16, suitable securing bolts or rivets are inserted, and to re-inforce the structure rings 21 may be placed against the outer surfaces of the heads and secured thereto by the same rivets which secure the cylindrical body in position, as will be readily understood.

At one edge of the opening 19, a flange 22 is provided on the body, said flange extending inwardly and being adapted to fit against the front closing plate 23 which is secured thereto and to a supporting bar 24 at its lower edge which extends longitudinally of the drum in substantially the radial plane of the opposite edge of the opening 19. The said closing plate 23 is disposed parallel with one radius of the drum, as shown clearly in Fig. 2, so that the inner edge of the plate is spaced from the opposite edge of the body of the drum, thereby leaving an uninterrupted opening through which the material may be fed into and discharged from the drum. The edges of this plate 23

are reinforced by and secured to angle-bars 25 which are arranged against the inner surface of the plate and follow the outline of the same, as will be readily understood 5 upon reference to Fig. 2. Within the drum and against the ends thereof, and also against the inner face of the closing plate or partition 23, I provide shelves 26 which are disposed at an angle to the heads of 45°, more 10 or less, and extend from the heads to the hollow shaft, as shown most clearly in Figs. 3 and 4. These shelves are constructed of steel plates each having a triangular portion 27 bent substantially at a right angle to its 15 main portion and extended from that edge most remote from the opening in the drum to form a partition whereby the material in the drum will be prevented from passing under the shelves and collecting therein, the 20 shelves and the partitions having flanges 27' through which fastening devices may be inserted to secure them to the heads 16 and the covering plate 23.

It will be observed, upon reference more 25 particularly to Figs. 3 and 4, that the shelves converge from the heads or ends of the drum toward the hollow shaft, so that the material deposited upon the shelves will be projected toward the center of the drum and fall 30 therefrom toward the lowest point of the drum. Within the drum, at a point away from the shelves and the opening in the drum, I provide a divider or deflector 28 which is substantially a rigid plate bolted 35 or riveted to the body of the drum and having its ridge 29 extending across the drum at an angle to the radius of the same. The parts should be so positioned within the drum that when the front closing plate 23 40 is vertical, the open space between the then lower edge of said plate and the front or free edge of the cylindrical body of the drum will be horizontal, the deflector 28 then extending from the lowest point of the drum 45 upwardly and rearwardly, so as to constitute a segment of the circle described by the body of the drum. The shelves will then be above the deflector and slightly in advance of the same.

50 The drum being in the position just described, the material to form the concrete is fed into the drum through the opening 19 and will at once, of course, drop to the lowest point of the drum and against the deflector 28. The drum being then rotated, so 55 that the opening 19 will move upward from the platform, the deflector 28 will be carried into the material placed in the drum, so that the said material will be separated and 60 caused to roll toward the ends of the drum. As the rotation of the drum continues the weight of the material will tend to keep the same at the lowest point of the drum, so that the deflector 28 will be carried entirely 65 through the said body of material and the

shelves 26 brought to the same. As the shelves are secured to the heads of the drum and converge therefrom toward the shaft, they will pass under the material so as to take up the same and cause it to roll toward the center of the drum, the discharge of the material from the drum being prevented by the plate 23. As the material reaches the lower ends of the shelves, it will drop therefrom and consequently fall upon the deflector 28 by which it will again be turned toward the ends of the drum, and this operation is continued until the ingredients have been thoroughly commingled. It will be understood, of course, that water to the desired quantity is admitted to the drum through the hollow shaft which is provided with perforations 30 to cause the water to discharge onto the material in the drum. The materials having been thoroughly 85 mixed, the drum is rotated in the opposite direction and the mixture will then work toward the opening 19 and be finally discharged through the same. The platform 4 furnishes a convenient support for the materials to be mixed, while they are being measured, and the operator may also stand upon the platform while depositing the material in the drum. When the mixing has been completed, the drum may be moved to 90 the point where the concrete is to be used, before the drum is rotated reversely to discharge the mixture.

It will be readily seen from the foregoing description, taken in connection with the accompanying drawings, that I have provided an exceedingly simple concrete mixer by which the materials may be thoroughly and rapidly commingled, and which is free of complicated gearing or agitators, so that 105 it may be produced at a low cost. The apparatus will be found especially desirable in plants for manufacturing concrete pipes or other similar articles which are formed in small molds, and a detailed reference to 110 its many advantages is believed to be unnecessary.

Having thus described my invention, what I claim as new, is:—

1. A concrete mixer comprising a rotary 115 drum having an opening through which material is fed and discharged, a deflector at one side of the drum remote from said opening and spaced from the ends thereof and having its greatest dimension in a radial plane of the drum to turn the material toward the ends of the drum, and inwardly projecting devices on the ends of the drum to cause the material to roll from the ends of the drum toward the deflector. 120

125 2. A concrete mixer comprising a rotary drum, a central deflector secured therein across an axial plane thereof to cause the material to flow toward the ends of the drum, and shelves secured to the ends of 130

the drum and converging toward the axis of the same to take up the material and discharge it upon the said deflector.

3. A concrete mixer comprising a rotary drum, a transverse deflector therein, and shelves consisting of plates bent at right angles, the greater portions of the plates extending from the ends of the drum at an angle thereto toward the deflector and the lesser portions of the plates extending from the free edges of the shelves to the ends of the drum.

4. A concrete mixer comprising a rotary drum having a longitudinal filling and discharging opening; a front plate extending from one edge of the said opening into the drum, a deflector within the drum on the transverse center thereof and at that side of the axis of the drum remote from the said plate, and shelves on the ends of the drum

immediately adjacent the said plate and converging toward the said deflector.

5. A concrete mixer comprising a rotary drum, a transverse deflector therein, shelves consisting of plates bent at right angles, the greater portions of the plates extending from the ends of the drum at an angle thereto toward the deflector and the lesser portions of the plates extending from the free edges of the shelves to the ends of the drum, and a plate extending longitudinally of the drum against the shelves parallel with the lesser portions of the same.

In testimony whereof I affix my signature in presence of two witnesses.

JOHN R. BOARDMAN. [L.s.]
